CLAIM

The ornamental design for a magnetic activation device, as shown and described.

DESCRIPTION

FIG. 1 is an angled perspective view of a magnetic activation device according to an embodiment of the claimed design. FIG. 2 is a front perspective view of the magnetic activation device of FIG. 1 shown in an open configuration.

FIG. 3 is a front view of the magnetic activation device of FIG. 1.

FIG. 4 is a rear view of the magnetic activation device of FIG. 1.

FIG. 6 is a top view of the magnetic activation device of FIG. 1; and,

FIG. 7 is a front cross-sectional view of the magnetic activation device of FIG. 1 taken along the line A-A' shown in FIG. 6.

The right side view is a mirror image of the left side view shown in FIG. 5.

The bottom view is a mirror image of the top view shown in FIG. 6.
